OIL CLARIFIER

William Robert Mobley, Miami, Fla.

Application December 29, 1930, Serial No. 505,334

2 Claims. (Cl. 210—47)

The invention herein described relates to a method of washing and clarifying oils and other light liquids and finds its principal employment in the removal of salt water, sand, emulsions and other impurities particularly in crude oil prior to refining.

I accomplish the objects of this invention by a process of washing thin films of oil submerged below their natural level in water or other suitable 10 cleansing solution or solutions in the manner described in the accompanying specification and drawing in which:

The figure is a vertical sectional view of an apparatus embodying and for the practice of my invention.

Similar numerals refer to similar parts throughout the view in which 1 is a receptacle having arranged therein a plurality of partitions or surfaces 2 provided with escapement ports or the like 3 and 4.

An intake pipe or conveyor 5 enters the receptacle 1 at any desired distance from the bottom of the said receptacle through which oil and emulsions may enter.

25 An outlet pipe 6 for the clarified oil leads from the top of the receptacle.

An intake pipe or conveyor 7 for the water or other cleansing solution enters the receptacle at or near the top as at 8.

30 An outlet pipe 9 for the water or cleansing solution and emulsions washed or removed from the oil leads from the receptacle at or near the bottom as at 10.

For example, in operation, water is admitted 35 into the receptacle 1 until it overflows or escapes from the pipe 9. As an example of operation with a lighter liquid and a heavier liquid, oil containing salt water is forced into the receptacle either by gravity or pressure through the pipe line

40 5 entering the receptacle at a point below its natural level. Due to the difference in specific gravity the oil rises to the under surface of the first partition shown from the bottom and passes in an upward direction through the escapement 45 port 3 thence to the lower surface of the next partition and so on until it reaches the top of the receptacle after which, due to its specific gravity it rises in pipe 6 from whence it may be conveyed to any desired receptacle.

50 During this entire operation water is passed through the device in an opposite direction to the oil and while the oil is spread in thin films over the under surfaces of the partitions the emulsions and other impurities are removed and carried out over the upper surfaces of the several par-

titions by the action of the water flowing in an opposite direction and allowed to pass through the several escapement ports 4 arriving at the exit 10 and passing out through the pipe 9. The upward course of the lighter liquid through the apparatus is indicated by the arrows *b* and the downward course of the heavy liquid is indicated by the arrows *a*. It will be observed that in each part or chamber of the tank the flows of the two liquids are opposite to each other, so that there are 10 formed in the operation of the apparatus, bodies of lighter and heavier liquids which are passed respectively upwards and downwards, the bodies of said liquids also passing each other horizontally or transversely in opposite directions.

15 It will be observed that the escapement ports 3 and 4 in the partitions project above and below the partition. It will be further observed that by this procedure that the port which extends in a downward direction conveys the cleansing solution below the film of oil on the under surface of the partition thus offering no interference. The escapement port extending in an upward direction conveys the oil to a desired distance above the lower level of the cleansing solution as it flows 20 along the surface of the partition. 11 and 12 are baffle plates arranged respectively at the exit 10 and at the entrance of the pipe 7.

25 It is to be understood that the oil outlet 6 and the water outlet 9 shall terminate at desired points 30 above and below each other, respectively, so that the proper proportions of water and oil shall be retained in the receptacle for efficient operation. Both of said outlet pipes terminate a considerable distance above the said receptacle.

35 While I have shown and described one adaptation of my invention I may employ any modification that fairly comes within the scope of same.

Having now described the nature of my invention and the manner in which same may be performed what I claim as new and desire to secure 40 by United States Letters Patent is:

1. A separator and purifier for liquids of lighter specific gravities, which consists of a tank having a plurality of partitions forming a 45 plurality of chambers, each of said chambers communicating with another by conduits connecting respectively with the top and bottom of each partition and extending into the interior of the next upper and lower chamber, the said 50 conduits in one partition being at the opposite side of each chamber to the said conduits in the next partition, discharge lines leading from the upper chamber and lower chamber for the light and heavy liquids respectively, said light liquid 55

discharge line terminating above the said heavy liquid discharge and both of said discharge lines terminating above the top of said chambers, and supply lines for the light and heavy liquids respectively leading into separate chambers at points above and below the source of the said heavier and lighter liquid discharge lines.

2. A purifier for liquids having in combination a receptacle provided with partitions separating the interior of the receptacle into chambers one above another, said partitions having downwardly extending conduits for the downflow of heavier

liquid arranged alternately at either side of the middle of the receptacle to cause lateral flow of the heavier liquid across the receptacle between said partitions, said partitions having upwardly extending conduits for the upflow of the lighter liquid, said conduits being arranged alternately at either side of the middle of the receptacle to cause lateral flow of the lighter liquid between said partitions in washing contact with and oppositely to the flow of said heavier liquid. 5 10

WILLIAM ROBERT MOBLEY.
